UNITED STATES PATENT OFFICE.

JAMES H. BELDIN, OF MALIN, OREGON.

ADJUSTABLE PROPELLER.

1,331,045.

Specification of Letters Patent. Patented Feb. 17, 1920.

Application filed December 1, 1917. Serial No. 204,941.

To all whom it may concern:

Be it known that I, JAMES H. BELDIN, a citizen of the United States, residing at Malin, in the county of Klamath and State 5 of Oregon, have invented new and useful Improvements in Adjustable Propellers, of which the following is a specification.

This invention relates to screw propellers, and more especially to those having adjustable blades; and the object of the same 10 is to produce an improved form of adjustment whereby the pitch of the blades can be simultaneously altered to such an extent as to cause the propeller to reverse its action while still rotating in the same direction.

The invention consists in novel means for effecting the adjustment of the blades while yet permitting their removal for repair or 20 substitution, all as hereinafter more fully described and claimed and as shown in the drawings wherein—

Figure 1 is a side elevation, Fig. 2 a plan view, and Fig. 3 an end elevation of one 25 type of my invention, while Fig. 4 shows various details thereof in perspective.

Fig. 5 is a side elevation and Fig. 6 a plan view of another type of my invention, while Fig. 7 shows various details in perspective.

Figs. 8 and 9 are slightly modified forms 30 of the forks, showing their arms as pivoted.

The main shaft 1 has a T-head 2 at its 35 front end, and each blade 3 has a tubular stem 4 at its inner end revolvably and removably fitting over one branch of the T-head. In the type shown on Sheet 1 the stem 4 is tubular and the branch is solid, whereas 40 in the type of my invention shown on Sheet 2 the stem is solid and the branches of the T-head are tubular as will be explained below. At the inner end of each stem an arm 5 projects rigidly in one direction and is 45 pierced with a hole 6, while a segment 7 projects rigidly in the opposite direction and carries a guide 8. The arm and segment may be of one piece, and they stand in a plane at right angles to the axis of the stem.

50 These elements are in reverse position with respect to the same elements on the other stem so that when the parts are assembled as best seen in Figs. 2 and 3, the arm of one stem projects through the guide of the other.

The setting mechanism comprises a lever

10 having a loop 11 in its body and its upper end pivoted at 12 to a bridge 13 carried by the frame 14, and a toothed sector 15 carried by a frame engaging a thumb latch 60 mechanism 16 on the lever. The sides of the loop are slotted as at 17, and pins 18 on rods 19 engage these slots. Said rods extend forward in parallelism with the main shaft and are connected by a ring 20 which 65 travels in a groove 21 formed around a hub 22 at the inner end of the fork 23, the stem of the fork and the hub itself being slidably mounted on the main shaft. The fork arms are provided with outstanding pins 24 70 which slidably engage eyes 25 swivelly mounted in holes 6 in the arms 5. Therefore when the lever is moved the rods 19 and ring are moved forward and backward. The ring causes the movement of the hub 75 and fork, and the pins on the fork are slidably mounted in the eyes 25 which latter are swiveled in the outer ends of the arms 5. These arms and therefore the stems 4 carried by them are thus turned on the 80 branches of the T-head 2 to set the blades 3 at the proper or desired angle. Meanwhile the main shaft 1 and the hub and fork continue their rotation, and the blades are revolved in the manner well understood. 85

The type of the invention shown on Sheet 2 is much the same with the exceptions above mentioned and others which follow from this exception. Each blade 33 has a solid stem 34 with a laterally projecting arm 35 90 at its inner end provided with a longitudinal slot 36. The main shaft has a tubular T-head 32 slotted along one side and closed by a filler 31 adapted to be held in the slots by clips 30. The lever mechanism, rods, 95 grooves and hub are the same, but the fork-arms 43 carry pins 44 and 45 one of which rises through the slot 36 in one arm 35 and the other of which depends through the slot 36 in the other arm. Said arms work 100 in slots 47 in the sides of the T-head and are arranged a little out of alinement with each other, and the filler may be notched as at 48 so that these slots extend into the filler when the latter is in place. 105

I have described my invention as applied to a propeller. While this is an article generally understood as working under the surface of the water, it may obviously be an air propeller for a flying machine. Also the 110 device might be an ordinary fan if it were desired to set its blades at a different angle,

I would not, therefore, be limited to the uses of this device, by whatever name it is called. The obvious purpose of the invention is to permit the operator by means of 5 the lever 10 to adjust the pitch of the two blades oppositely and simultaneously. When these stand oblique in one direction, with the shaft revolving constantly, a current will be set up in the liquid or air in 10 one direction, when the blades are adjusted "edge on" no effect will be produced, and when they are adjusted to such an extent that they stand oblique in the opposite direction, said current would be reversed—all 15 as well understood and needing no further detailed explanation.

Instead of making the fork-arms 23 rigid and providing them with pins 24 to engage holes 6 as in Fig. 4, or instead of making 20 the fork-arms 43 rigid and providing them with pins 44 and 45 to engage slots 36 as in Fig. 7, I may make the fork-arms 50 separate from the shank of the fork as seen in Fig. 8 and pivot them thereto as at 51, providing their outer ends with eyes 52 which are in turn pivoted to the arms 5 or 35 in a manner which will be clear, or, as seen in Fig. 9, I may make the fork-arms 53 slightly curved in their length, and of course they 30 may be longer or shorter as required by the proportion of parts. This modification does away with the sliding of the pin 24 in the eye 25 or the sliding of the pins 44 and 45 in the slot 36, but the principle of my invention is unchanged.

What is claimed as new is:—

1. The combination with a main shaft carrying a T-head at its front end, a pair of blades having tubular stems rotatably 40 mounted on the branches of said T-head, and on each stem an arm projecting in one

direction and a segment in the other, the arm of one stem overlying the segment of the opposite stem; of a fork having a tubular shank slidably mounted on said main shaft, pins projecting outward from the fork-arms, and eyes swiveled in the outer end of the stem-arms and slidably engaged by said pins.

2. The combination with a main shaft 50 carrying a T-head at its front end, a pair of blades having tubular stems rotatably mounted on the branches of said T-head, an arm at the inner end of each stem projecting in one direction and a segment projecting in the other, both standing in a plane at right angles to the axis of the stem, and a guide carried by each segment and adapted to loosely embrace the arm on the other stem; of a fork having a tubular shank 60 slidably mounted on said main shaft, means for adjusting it longitudinally, and connections between each fork arm and one of the stem-arms, for the purpose set forth.

3. The combination with a main shaft 65 carrying a T-head at its front end, a pair of blades having tubular stems rotatably mounted on the branches of said T-head, an arm at the inner end of each stem projecting in one direction and a segment projecting in the other, both standing in a plane at right angles to the axis of the stem, and a guide carried by each segment and adapted to loosely embrace the arm on the other stem; of a fork having a tubular shank 70 75 slidably mounted on said main shaft, means for adjusting it longitudinally, pins projecting outward from the fork-arms, and eyes swiveled in the outer end of the stem-arms and loosely receiving said pins.

In testimony whereof I affix my signature.
JAMES H. BELLDIN.
